Fig. 1.

Fig. 2.

Fig. 3.

Fig. 4.

FIG. 1 is a perspective view of a cigarette package showing my new design; and

FIG. 2 is a top plan view thereof;

FIG. 3 is a perspective view of a modified form of a cigarette package showing my new design wherein the top flap is shortened on one end; and

FIG. 4 is a top plan view thereof.

The drawing is shaded to indicate contrasting colored areas, no particular colors being intended.

The dominant feature of my design resides in the portions shown in full lines.

This application is a continuation of my earlier filed applications Serial No. D. 73,323 and D. 73,324, both filed on January 28, 1963, and now abandoned.

I claim:

The ornamental design for a cigarette package, substantially as shown and described.
